tion of Delaware

Application January 25, 1941, Serial No. 375,893

9 Claims. (Cl. 179—171)

This invention relates to an amplifier in which a voltage from a single source is amplified and converted into a two-phase or push-pull source. More particularly the invention relates to a direct current amplifier for amplifying and converting potentials from a "single-ended" circuit into push-pull potentials.

The use of a single tube for amplifying voltages from a "single ended" source and converting these voltages into a pair of voltages, having a 180 degree phase relation with respect to each other, has been shown in the patent of Charles Travis 1,909,239 which issued on May 16, 1933. The circuits proposed in the Travis patent are suitable for use with alternating current signals but they are not adaptable to direct current signals. The principal difficulty in the circuits of the above mentioned patent is that blocking capacitors are used to prevent undesired bias potentials from being applied to the input circuits of the push-pull amplifier which follows the first amplifier. If these capacitors are eliminated, the bias potentials applied to the input of the push-pull amplifier would unbalance, and perhaps make inoperative, that amplifier. The unbalanced amplifier would not perform the desired function.

One of the principal objects of the present invention is to provide means whereby an amplifier and associated circuit may be used to amplify and convert a single-phase current into an amplified current of two phases. Another object is to provide means for the amplification of a direct current whereby currents of equal magnitude and opposite sense, with respect to each other, may be obtained. A further object is to provide means in a direct current amplifier whereby currents from a "single-ended" circuit may be amplified and converted into currents suitable for application to a push-pull amplifier.

The invention will be described by referring to the accompanying drawing in which Figure 1 is a schematic circuit diagram of one embodiment of the invention; Figure 2 is a schematic circuit diagram of an embodiment of the invention in which a single-ended circuit may be connected to a push-pull amplifier provided with an alternating current output circuit; and Figure 3 is a graph illustrating the operation of the circuit.

Referring to Fig. 1, input terminals 1 and 3 are connected, respectively, to the grid of an amplifier 5 and to the grounded mid-point 7 of a pair of B-batteries EB1 and EB2. The anode of the amplifier 5 is connected through a resistor R1 to the plus terminal of battery EB1. The cathode

5 of the amplifier 5 is connected through a resistor R2 to the negative terminal of the battery EB2. The remaining battery terminals are connected to ground as shown. A potentiometer comprising resistors R3 and R4 is connected between the cathode of the amplifier and the positive terminal of the battery EB1. A second potentiometer comprising resistors R5 and R6 is connected between the anode of the amplifier and the negative terminal of the battery EB2. The movable contacts 9 and 11, respectively, of the potentiometers are connected to output terminals 13, 15. The output voltages E2a and E2b appear between the output terminals 13 and 15, and the intermediate battery terminal or ground.

10 The preferred practical use of the device is an adjustment producing a truly push-pull output, namely, one in which the amplified signals are equal in magnitude and opposite in phase. In this practical use of the device, the batteries EB1 and EB2 are preferably of equal potential. The resistors R1 and R2 are preferably of equal value and the sum of these resistors R1 and R2 is chosen to represent a suitable loading for the 15 amplifier 5. The sum of the resistances R3 and R4 preferably equals the sum of the resistances R5 and R6. Furthermore, the sum of the resistors R3 and R4 is preferably of the order of 10 times R1. The final practical requirement is 20 that the ratio of R3 to R4 is equal to the ratio of R6 to R5 as will hereinafter be explained.

25 The operation of the circuit is as follows: The current through resistors R1 and R2 is the same. Therefore, the voltage drop across R1 will equal the voltage drop across R2, since R1 equals R2. If a positive potential is applied to the terminal 1 with respect to terminal 3, the current through the resistors R1 and R2 will be increased over the value which is maintained in the absence of 30 an input signal. The increased current will be accompanied by increased voltage drops across the resistors R1 and R2. It follows that the voltages between the anode and ground and the voltages between the cathode and ground will change 35 in a "push-pull" manner as will the voltages E2a and E2b. By suitably adjusting the potentiometers the ratio of R3 to R4 and R6 to R5 may be determined so that the voltage changes in the 40 output of the amplifier will be equal and opposite with respect to each other. Furthermore, the 45 quiescent or no signal output voltages for this adjustment, will be equal in magnitude and opposite in polarity. It follows that the quiescent voltages can be adjusted to any value between 50 EB1 (or EB2) and the difference in voltage be-

tween EB1 (or EB2) and the drop across R or (R2).

By way of example, reference is made to Fig. 3 with a zero input signal E1. The potentiometers may be adjusted so that

$$\frac{R3}{R4} = \frac{R6}{R5}$$

and E2a will equal E2b, and the steady voltage equals zero. Thus adjusted, the sloping lines in the graph represent the corresponding changes in output current as the input potential is made more negative or more positive.

It is not intended that the adjustment of this circuit be limited to truly push-pull operation. Any number of combinations of E2a and E2b can be obtained dependent on the adjustment of the ratios

$$\frac{R3}{R4} \text{ and } \frac{R6}{R5}$$

The quiescent output voltage can be adjusted to be unequal in magnitude and opposite in polarity or of the same polarity. It should be noted that the signal outputs are always of opposite phase, one with respect to the other. The amplitude of the signal outputs and the magnitude and polarity of the quiescent voltages are interrelated.

It should be understood that the power source for the amplifier is not to be limited to batteries and that the power may be applied from a suitable generator or rectifier and filter. In connection with power sources other than batteries, it should be evident to those skilled in the art that this circuit (particularly the truly push-pull adjustment) is relatively insensitive to changes in supply potential. Furthermore, any type of push-pull output amplifier may be used, as for example, the a-c amplifier of Fig. 2 in which the input potentials E2a, E2b are applied to the push-pull amplifiers 17 and 19, respectively. The output circuits of the push-pull amplifiers include a conventional output transformer 21.

I claim as my invention:

1. An amplifier for amplifying and converting a single steady current into currents of opposing characteristics including an amplifier having grid, anode, and cathode electrodes, a power source having end terminals and an intermediate terminal, resistors connecting respectively said end terminals and said anode and cathode electrodes, means for applying between said grid and intermediate electrode currents to be amplified, and a pair of potentiometers respectively connected between said anode and one of said end terminal and between said cathode and the other of said end terminal for deriving directly said currents of opposing characteristics.

2. An amplifier for converting a direct current into two direct currents of opposing characteristics including an amplifier having grid, cathode, and anode electrodes; a power source having a positive terminal, a negative terminal, and an intermediate terminal; a pair of resistors connecting respectively said anode to said positive terminal and said cathode to said negative terminal; means for applying between said grid and said intermediate terminal the direct current to be converted, a pair of potentiometers connected respectively between said anode and said negative terminal and between said cathode and said positive terminal; and means connected respectively to each of said potentiometers for deriving between said respective connecting means and

said intermediate terminal said direct currents of opposing characteristics.

3. An amplifier for converting a direct current into two equal direct currents of opposing characteristics including an amplifier having grid, cathode, and anode electrodes; a power source having a positive terminal, a negative terminal, and an intermediate terminal; a pair of resistors of equal value connecting respectively said anode to said positive terminal and said cathode to said negative terminal; means for applying between said grid and said intermediate terminal the direct current to be converted, a pair of potentiometers connected respectively between said anode and said negative terminal and between said cathode and said positive terminal; and means connected respectively to each of said potentiometers for deriving between said respective connecting means and said intermediate terminal said direct currents of opposing characteristics.

4. An amplifier for converting a direct current into two equal direct currents of opposing characteristics including an amplifier having grid, cathode, and anode electrodes; a power source having a positive terminal, a negative terminal, and an intermediate terminal; a pair of resistors of equal value connecting respectively said anode to said positive terminal and said cathode to said negative terminal; means for applying between said grid and said intermediate terminal the direct current to be converted, a pair of potentiometers connected respectively between said anode and said negative terminal and between said cathode and said positive terminal; and means connected respectively to each of said potentiometers for deriving between said respective connecting means and said intermediate terminal said direct currents of opposing characteristics.

5. An amplifier for converting a single variable current into two currents which vary in opposite sense including an amplifier having grid, cathode, and anode electrodes, a power source having positive and negative terminals and a center tap, a pair of resistors of similar value connected respectively between said positive terminal and said anode and between said negative terminal and said cathode, means for applying said single phase current to said grid and center tap, output terminals for obtaining said currents between said center tap and voltage points intermediate said anode and said negative terminal and said cathode and said positive terminal, and means for adjusting said output terminals so that a predetermined current is obtained between each of said output terminals and said center tap.

6. An amplifier for converting a single variable current into two currents which vary in opposite sense including an amplifier having grid, cathode and anode electrodes, a power source having positive and negative terminals and a center tap, a pair of resistors of similar value connected respectively between said positive terminal and said anode and between said negative terminal and said cathode, means for applying said single phase current to said grid and center tap, a pair of potentiometers connected respectively between said anode and said negative terminal and between said cathode and said positive terminal, and means for adjusting said potentiometers so that said currents are obtained between the ad-

justable contact of each of said potentiometers and said center tap.

7. An amplifier for converting a single variable current into two currents which vary in opposite sense including an amplifier having grid, cathode and anode electrodes, a power source having positive and negative terminals and a center tap, a pair of resistors of similar value connected respectively between said positive terminal and said anode and between said negative terminal and said cathode, means for applying said single phase current to said grid and center tap, a pair of potentiometers connected respectively between said anode and said negative terminal and between said cathode and said positive terminal, and means for adjusting said potentiometers so that zero quiescent voltage with respect to said center tap is obtained between the adjustable contact of each of said potentiometers and said center tap and said two variable currents are obtained between said contacts and said center tap.

8. The combination of end and intermediate

power supply terminals, a pair of direct current circuits including reversely arranged impedance sections connected in parallel between said end terminals, means for similarly varying the current through one pair of the opposite end sections of said circuits, and means connected between said intermediate terminal and the other opposite end sections of said circuits for deriving voltages displaced in phase from one another.

9. The combination of end and intermediate power supply terminals, a pair of direct current circuits including reversely arranged impedance sections connected in parallel between said end terminals, an electron discharge device provided with an input circuit including said intermediate terminal and with an output circuit including one pair of the opposite end sections of said circuits, and means connected between said intermediate terminal and the other pair of the opposite end sections of said circuits for deriving voltages displaced in phase.

ADOLPH R. MORGAN.
